Inventor
Henry E. Merrill,

By his Attorney

C. B. Humphrey.

UNITED STATES PATENT OFFICE.

HENRY E. MERRILL, OF AKRON, OHIO, ASSIGNOR TO THE E. H. MERRILL COMPANY, OF SAME PLACE.

PRESS FOR EARTHENWARE VESSELS.

SPECIFICATION forming part of Letters Patent No. 368,956, dated August 30, 1887.

Application filed May 13, 1887. Serial No. 238,093. (No model.)

To all whom it may concern:

Be it known that I, HENRY E. MERRILL, a citizen of the United States, and a resident of the city of Akron, in the county of Summit 5 and State of Ohio, have invented new and useful Improvements in Presses for Earthenware Vessels, of which the following is a specification.

My invention has relation to improvements 10 in that class of presses for earthenware vessels in which the crock is formed by first forcing the tempered clay through an annular orifice between an outer case and inner mandrel on a bottom of similar material held against 15 the annular orifice until the parts unite by a movable plate, and then releasing the plate and forcing the clay through the annular orifice to the desired length and cutting it off.

In operation difficulty is found in separating 20 the crock-bottom in its plastic state from the mandrel-bottom. To obviate this various devices have been adopted, as downward-opening valves, shown in the patent to M. J. Housel, No. 197,853, and a loose base having a 25 downward motion, shown in patent to W. E. Dempsey and myself, No. 310,705, neither of which has been effective in all cases. This difficulty is especially noticeable where the 30 cross-section is large, and where it is other than circular, as in square or other polygonal forms.

The object of my invention is to overcome 35 this difficulty.

It consists in the devices illustrated in the 40 accompanying drawings, as hereinafter described and claimed.

In the accompanying drawings, Figure 1 is a central vertical section of a press embodying my invention, and Fig. 2 an inverted 45 plan of the mandrel.

The clay-cylinder A, in which is the piston B, moved by the rods C C', has a lower head, D, which forms the outer case of the annular orifice, and in this instance is adapted to 50 the construction of square crocks with round corners. Centrally within this case is the hollow mandrel E, suspended from a support, F,

consisting of a rim and a hub connected by radial arms.

In the base of the mandrel E is an annular 50 channel between its outer edge and center, in which fits a ring, G, the outer face of which is flush with the base of the mandrel. The ring G is attached by rods g to a number of radial arms projecting from a hub, H, inside 55 of the mandrel. This hub is keyed to a shaft, J, which passes upward through the support F and piston B, and is pivoted to one end of the lever I.

Below the point of discharge and concentric with it is a plate, K, with a raised rim attached to the rod L, by which it is raised to and lowered from the press, and is arranged by devices (not shown) to be locked against the head D.

In operation the cylinder A is charged with 60 plastic clay. A mass of the same material sufficient to form the crock-bottom is placed on the plate K, which is raised and locked against the head D. Pressure is then applied 70 to the clay in the cylinder until it unites with the mass on the plate K, when the latter is released and descends as the clay is forced through the annular orifice until the proper length of crock is reached. Simultaneously 75 with the release of the plate K the ring G is released and thrown downward, thereby pushing the crock-bottom from the base of the mandrel, and allowing air to enter around the rods g.

I do not confine my invention to the exact 80 mechanical details here shown, as the mandrel may be suspended by a hollow shaft from the upper cylinder-head, as shown in the patents before cited. The shaft J may be 85 hollow to supply air to the inside of the mandrel. The edges of the ring G may be beveled and other modifications made, as the necessities of each case may require or as experience may dictate.

I claim—

1. In a press for earthenware vessels, the combination, with a mandrel having an annular channel in its base, of a ring which fits

in said channel, and is provided with devices, such substantially as shown, by which it is forced from and drawn into said channel, substantially as shown, and for the purposes specified.

2. The combination, with the mandrel E, having an annular channel in its base, of the ring G, supported by the rods g from the arms of the hub H, the rod J, and lever I, all

constructed and arranged substantially as to shown, and for the purpose specified.

In testimony that I claim the foregoing I have hereunto set my hand this 10th day of May, A. D. 1887.

HENRY E. MERRILL.
